UNITED STATES PATENT OFFICE

WILLIAM ANDREW O'BRIEN, OF SAN FRANCISCO, CALIFORNIA

DESIGN FOR A COMBINED GAME BOARD AND TRAY

Application filed May 27, 1931. Serial No. 40,012. Term of patent 14 years.

To all whom it may concern:

Be it known that I, WILLIAM ANDREW O'BRIEN, a citizen of the United States of America, residing at San Francisco, in the county of San Francisco and State of California, have invented a new, original, and ornamental Design for a Combined Game Board and Tray, of which the following is a specification, reference being had to the accompanying drawings, forming a part thereof.

Figure 1 is a top plan view of a combined game board and tray showing my new design, and

Figure 2 is a side elevation of the same.

I claim:—

The ornamental design for a combined game board and tray, substantially as shown.

WILLIAM ANDREW O'BRIEN.
